UNITED STATES PATENT OFFICE.

WILLIAM B. BOWMAN, OF WILKES-BARRE, PENNSYLVANIA.

BOX.

1,145,665.

Specification of Letters Patent.

Patented July 6, 1915.

Application filed September 24, 1913. Serial No. 791,592.

To all whom it may concern:

Be it known that I, WILLIAM B. BOWMAN, a citizen of the United States, residing at Wilkes-Barre, in the county of Luzerne and 5 State of Pennsylvania, have invented certain new and useful Improvements in Boxes, of which the following is a specification, reference being had to the accompanying drawings.

10 This invention relates to paper boxes and it more particularly relates to an improved form of fastening and strengthening device for paper boxes.

One of the objects of the invention is to 15 provide paper boxes which may be of any size or shape, with an ever-ready tying tape or string in such position that it cannot be removed from the box without untying or severing it, so that the box may be quickly 20 and securely sealed to avoid tampering by delivery boys, etc.

Another object of the invention is to provide a paper or cardboard box with a tape or string which is fixedly secured thereto 25 and is of a proper length and of the proper size and strength for tying the particular size and design of box to which it is secured, so as to avoid the usual inconvenience of carrying the box to some particular part of 30 a store to be wrapped and tied.

Another object of this invention is to provide a box with a tie string secured thereto and with adjacent stiffening and strengthening means, so that the usual necessity for 35 wrapping the box in paper is avoided, thereby effecting a great saving in paper and time.

In the accompanying drawings which 40 supplement this specification, Figure 1 is a top plan view of the box, the cover being removed and the strengthening strip being turned back; Fig. 2 is a fragmental vertical section through the box and cover; Fig. 3 is an enlarged fragmental detail view, illustrating the strengthening strip and washers in vertical section; Fig. 4 is a fragmental 45 bottom plan view; Fig. 5 is an enlarged fragmental detail view, illustrating the tie element in section; and Fig. 6 is a transverse vertical sectional view adjacent to the tie element.

In these drawings in which similar reference characters correspond with similar parts throughout the several views, the body 50 10 of the box and the top 11 may be of any preferred size and shape, according to the

purpose for which it is intended and the merchandise which it is intended to pack therein. The bottom 10' of the body 10 is apertured at opposite sides, adjacent to its 60 edge portions, as at 10a. Perforated disks or washers 12 are glued or otherwise secured on the inner and outer surfaces of the bottom with their apertures in registry with the aperture 10a, so as to constitute an eyelet through which the tie string or tape 13 is passed. Obviously, any other form of eyelet may be substituted for the disks 12 and the eyelet or disks may be made from any preferred and suitable material. The 65 stiffening strip 14 is glued or otherwise secured to the bottom 10' and to the sides 10b, and this stiffening strip 14' may have its end portions turned down at the top, although, obviously, this specific arrangement is not 70 absolutely essential; but it is essential that the strengthening strip extend to the top of the wall 10b, so as to strengthen said wall and thereby strengthen the cover 11 where it rests upon the wall and where the tie 75 string hereinafter described passes thereover.

The medial portion of the tie element 13 is secured between the bottom 10' and the medial portion of the strip 14, and the end 80 portions which project through the eyelets 12 may be passed directly outward, upward and over the box top 11, whence they may be united by tying or in any other suitable way. However, it may be found preferable 85 to pass the tie elements in lapped relation back under the bottom 10', as illustrated in Fig. 4, so as to add greater strength to the box, and accordingly the ties are made sufficiently long for tying the box in the last 90 described way.

It is obvious that any desired number of the tying device described in the foregoing may be applied to a box, either at its medial portion, adjacent its end portions, or both; 100 and it is also obvious that the ties 13 and strips 14 may be disposed either longitudinally or laterally of the box.

From the foregoing it will be seen that I have provided a device of this character 105 which is fully capable of attaining the desired objects, as specified in the foregoing, in a thoroughly practical and efficient manner.

While the accompanying drawings illustrate what I believe to be the preferred embodiment of my invention, it is to be under-

22
stood that the invention is not limited thereto, but that various changes may be made in the construction, arrangement and proportions of the parts without departing 5 from the scope of the invention as defined in the appended claim.

It will be readily understood that while I have shown and described the strips 14 as glued or otherwise secured to the bottom 10 and side walls of the receptacle, it will be readily apparent that they may be fastened by sharp pointed tacks or specially constructed fastening clamps. It will also be apparent that these tacks or clamps may be 15 arranged at any suitable point and spaced any distance apart but are to be so arranged that the strips 14 will be securely held in position.

What I claim is:—
20 A device of the class described including

a paper box having a pair of oppositely disposed eyelets in the bottom thereof adjacent to the opposite edges thereof, a tie element having its medial portion disposed on the bottom of the box and having its end portions extending downward through the eyelets, a cover for the box, and a strengthening strip having its medial portion disposed upon the bottom of the box and upon the tie element thereon and secured to said bottom 25 and said tie element, said strengthening strip having its end portion turned up against opposite walls of the box and extending to the top thereof.

In testimony whereof I hereunto affix my 30 signature in the presence of two witnesses.

WILLIAM B. BOWMAN.
